UNITED STATES PATENT OFFICE.

JOHN W. WAITZ, OF OIL CITY, PENNSYLVANIA.

APPARATUS FOR FORCING FLUID FROM WELLS.

No. 886,280.

Specification of Letters Patent. Patented April 28, 1908.

Application filed October 17, 1903. Serial No. 177,488.

To all whom it may concern:

Be it known that I, JOHN W. WAITZ, a citizen of the United States, residing at Oil City, in the county of Venango and State of Pennsylvania, have invented certain new and useful Improvements in Apparatus for Forcing Fluid from Wells; and I do hereby declare the following to be a full, clear, and exact description of the invention, such as 10 will enable others skilled in the art to which it appertains to make and use the same.

My invention relates to improvements in apparatus for forcing fluid from wells. It is designed especially for oil wells but may 15 of course be used in any kind of well or for the purpose of forcing fluid from one height to another.

This invention covers a specific improvement over my former applications, Serial No. 20 121,223, filed August 27, 1902, and Serial No. 152,978, filed April 16, 1903. These applications covered apparatus for flowing and regulating the flow from oil or Artesian wells and for partially saving and utilizing the 25 motor fluid, usually compressed air.

I have now devised an apparatus whereby practically all of the surplus motor fluid remaining in the supply pipe and pocket in a well that has been flowed can be saved and 30 utilized or compounded from one well to another.

The special feature of my present invention therefore is the saving or utilizing of practically all of the motor fluid or compressed air after it has done its work of raising the fluid in a well to the surface and then compounding the same to flow other wells in succession.

My invention also comprises means whereby 40 a signal is given by a fluid pressure mechanism when a well has been temporarily discharged of fluid and means for regulating the flow of motor fluid to each well from one central station.

My invention is especially designed for 45 use with a number of wells operated from a single central station, at which station an air compressor is used which compresses the air to a high pressure, from four hundred to 50 one thousand pounds, for example, and then turning into the various wells the compressed air which is an expansible motor fluid.

With these objects in view my invention 55 consists in the construction and combinations of parts as hereinafter described and claimed.

In the accompanying drawings:—Figure 1 is a vertical section of an oil well with parts of my apparatus therein. Fig. 2 is an enlarged vertical section of a pocket or chamber. Fig. 3 is a perspective view of an air compressor as adapted for use with the other parts of my apparatus. Fig. 4 is a diagrammatic view showing the air compressor and system of valves and piping. Fig. 5 is a cross section of the valve mechanism for equalizing the back pressure flow. Fig. 6 is a cross section of the automatic spring valve used for the purpose of admitting atmospheric air into the back pressure cylinder. Fig. 7 is a cross section of a valve used to prevent the escape of fluid pressure from one well to another, and Fig. 8 is a cross section of the fluid pressure signal mechanism.

In carrying out my invention I provide for each well a chamber or pocket consisting of the shell 1 provided with removable heads 2 and 3. This pocket is lowered through the casing 4 of a well to the oil bearing rock and is provided with an inlet 5 at its lower end, provided with a check valve 6 of any suitable construction, which valve permits the easy inflow of oil but prevents any escape thereof downward through the bottom of the pocket into the well. An oil discharge pipe 7 passes through the casing head 9 of the well into the pocket, its lower end being adjacent to the lower end of the pocket and being provided with an inlet 10 and a check valve 11 of suitable construction. The casing 4 may have around it a secondary casing 12 forming a shoulder on which the casing head 9 may rest to keep water or foreign substances from getting into the well if this is desired. The casing head is provided with screw threaded openings 13 and 14 which may be either left open or into which pipes may be screwed for the purpose of conducting away the gas from the well should the well prove to be gas-producing. An air supply pipe 8, smaller in diameter than the discharge pipe, extends from the central power station and passes down through the casing head 9 and through the top of the pocket. The supply pipe 8 may just pass through the top of the head 2 as shown in Fig. 2, or it may extend further down into the pocket if desired and as described in my previous applications.

When sufficient oil has accumulated in the pocket of a well, fluid under pressure is forced

down the supply pipe 8 which closes the valve 6 and then forces the oil up through the discharge pipe 7 into any suitable receptacle. In deep wells air under high pressure is used, anywhere from four hundred to one thousand pounds. After such a well has been completely flowed and the air supply cut off, there still remains a large amount of compressed air under high pressure in the supply pipe and pocket. By turning this compressed air in another well, about one-half of the fluid pressure can be utilized, so that when a second well is to be flowed the surplus air from the first well already flowed having been turned into said second well, the air in the supply pipe in said second well will be under about half the pressure required for flowing said second well, in other words, anywhere from two hundred to five hundred pounds. By my present invention which comprises the combination of a back pressure cylinder and a free air or auxiliary cylinder and a system of pipes and valves I have devised a means whereby practically the whole 25 of said surplus fluid under pressure remaining in the supply pipe and pocket of the well after it has been flowed can be saved and utilized.

In Fig. 3 is shown an air compressor as 30 adapted for use in my apparatus which consists of two cylinders, a back pressure cylinder 15 and an auxiliary or free air cylinder 16. The belt pulley 17, crank 18, pitman 19, cross heads 20 and bed plate 21 are all of the 35 usual construction. The details of the air compressor such as the water jackets, etc., have not been shown at all and have been merely indicated, as they are of the usual type.

To the back pressure cylinder 15 is delivered the surplus motor fluid remaining in the supply pipe and pocket of a well after it has been flowed through the pipe 22. This surplus fluid under pressure, however, may be 45 either employed by directly returning it to the back pressure cylinder 15 in which it is put under a still higher pressure, or it may be delivered directly into the supply pipe of another well, in which case the air or motor fluid in said second well will have about half the pressure required to flow said well before additional motor fluid is turned into said second well from the main supply pipe. As there is necessarily some escape or waste of 55 air when a well is flowed into an open receptacle, since a part of the air which forces the oil along will escape just as the last part of the charge of oil is delivered into the receptacle, some means for providing an additional supply of air must be used, or in other words, air cannot be used over and over again passing from the cylinder 15 to a well and then back into said cylinder without replenishing the supply of air. I therefore use the free 60 air or auxiliary cylinder 16, shown in Fig. 3.

This cylinder draws in air from the atmosphere only and supplies air under pressure to about equalize the amount compressed by the back pressure cylinder, said back pressure cylinder being supplied from the wells 70 that have been flowed. When the free air or auxiliary cylinder 16 drives into the supply pipe more air than is required to compensate for the waste, this simply adds to the amount of the compressed air and does no 75 harm.

In Fig. 3 I have shown a single air compressor, but it is of course obvious that a compound or series air compressor could be used if desired. The auxiliary cylinder 16 is 80 provided with an air inlet pipe 23 to admit atmospheric air, as shown in Fig. 4. The compressed air as it leaves the back pressure cylinder 15 is forced through the pipe 24 and into an after cooler of any suitable construction (not shown) or directly into the main supply pipe 25 which supplies compressed air to all the wells. The air as it leaves the auxiliary cylinder 16 passes through the pipe 26 either into an after cooler or directly into 90 the supply pipe 25 which supplies the well.

It sometimes happens that the air from wells that have been flowed is not returned rapidly enough to the back pressure cylinder 15 through the pipe 22 to keep up an adequate 95 air supply in said cylinder 15, as for example, when the air from one well has been turned directly into a second well without returning it to the back pressure cylinder 15. I have therefore provided means whereby there 100 may be drawn into the back pressure cylinder under such conditions atmospheric air through the open pipe 27, which is provided with a valve shown on an enlarged scale in Fig. 6. This valve consists of a casing made 105 in two parts 28 and 29 screwed together, the latter part being provided with a cross bar 30, through the central perforated boss 31 of which passes a valve stem 32 provided with a rounded valve 33 which fits in the correspondingly shaped socket in the casing 28. Through the stem 32 passes a pin 34, and between this pin and the cross piece is a spring 35 which is just strong enough to normally hold the valve 33 out of contact with its seat. 110

If none of the back pressure air is supplied through the pipe 22, the valve 33 will be kept off its seat and atmospheric air will be permitted to enter the cylinder 15 freely; on the other hand, when air under pressure 115 comes back through the pipe 22 into the cylinder 15, it closes the valve 33 and prevents the loss of the air under pressure which is coming in through the pipe 22.

The back pressure pipe 22 is connected 120 with all the wells, and as the pressure in this pipe varies greatly, from fifty to five hundred pounds when the back pressure air is returning from the wells, and in some instances running down even to zero, I have devised a 125 130

means whereby the back pressure air is delivered through the pipe 22 to the cylinder 15 under a uniform pressure, which means also serves to prevent any air from the cylinder 15 from being forced backward through the pipe 22, although ordinary check valves can be used to prevent this if desired; for example, a check valve might be used in the T-joint 36 which connects the pipe 22 with the cylinder 15. This regulating means is shown in Fig. 4 and a portion of it is shown on an enlarged scale in Fig. 5. Within the pipe 22 is a valve which is operated by the lever 37. This lever in turn is operated by the centrally pivoted arm 38 carried on arm or standard 39 attached to the head 40 of the regulating means. The lever 37 is provided with a number of perforations 41 whereby the movement of the controlling valve may be varied. Screwed into the head 40 is a valve casing 42, and in this valve casing is a piston 43 provided with a piston rod 44 which is pivotally attached to the arm 38. The piston rod 44 passes through an ordinary stuffing box in the head 40. A spring 45 surrounds said piston rod and normally holds said piston down against the bottom of the casing 42, thereby closing the main back pressure pipe. In the casing 42 is screwed a small escape pipe 46, provided with a pet cock 47. This is for the purpose of allowing any air which may leak around the piston 43 to escape into the atmosphere.

In some cases I have thought it advisable to keep on hand a supply of motor fluid under pressure to supply the back pressure cylinder with fluid pressure to flow the first well, the air compressor having been shut down, or for other unusual emergencies, and in such cases I employ an ordinary storage tank (not shown) which is connected or placed between the back pressure cylinders and the supply pipe, suitable valves being of course provided at the supply and delivery openings of such storage tank.

As it is necessary to know at the central station when a well or a number of wells have been flowed, I have devised a signal mechanism operated by fluid pressure. A series of these mechanisms are shown in Fig. 4 and one of them is shown in cross section on an enlarged scale in Fig. 8. This signal mechanism consists of a valve casing 48 to which is screwed a head 49 provided with an ordinary stuffing box. To the head 49 is fastened an upright arm 50 provided with a graduated scale. Within the casing 48 is a piston 51 carrying a piston rod 52 which is provided with a pointer 53. A spring 54 surrounds the piston rod 52 and normally holds the piston 51 down against the bottom of the casing 48, which casing is provided with a small escape tube 55, provided with a pet cock 56 to allow for the escape of any air that may leak around the piston 51. One of these signal

mechanisms is mounted on each of the branch supply pipes that leads to each individual well as shown in Fig. 4, in which 48, 48^a and 48^b represent the cylinder casings of the signal mechanisms, and in which 57, 57^a and 57^b represent the branch supply pipes for each of the individual wells which are connected to the main supply pipe 25, these branch supply pipes each having a controlling valve therein, numbered 58, 58^a and 58^b. 75 Each one of these branch supply pipes is connected by the pipes 22^a, 22^b and 22, respectively, with the back pressure pipe 22, and valves 59, 59^a 59^b are provided which are ordinarily closed during the operation of flowing the well and opened after this operation is completed. Pipes 60, 60^a and 60^b are used which connect the supply pipe of one well with the supply pipe of the succeeding well, and valves 61, 61^a and 61^b are arranged to 85 open or close the connections between the supply pipes 57, 57^a and 57^b with the pipes 60, 60^a and 60^b, respectively.

When it is desired to flow the first well after the air compressor is put in operation, 90 the valves 59 and 61 are closed and the valve 58 opened. The air is then delivered through the pipe 57 into the pocket of the first well, discharging the oil that has accumulated in said pocket. This lifts the pointer 53 of the 95 corresponding signal mechanism moving it along the scale 50 up to the maximum pressure under which the particular apparatus is designed to work, a pressure of five hundred pounds being usually required. After the 100 oil has been driven out of the pocket of this well and has been elevated to the surface of the well the resistance at once becomes less, the air pressure in the pocket and the pipe 57 becomes less, and the pointer 53 begins to 105 drop over the scale. The valve 58 is then closed and the valve 59 opened, thereby cutting off the supply of air from the well that has been flowed and allowing the air still remaining in the pocket to escape back through 110 the pipes 22^a and 22 into the back pressure cylinder where it is used over again and its pressure utilized. Instead, however, of allowing the air to escape directly into the back pressure pipe 22, in some instances it is desirable to turn it into a second well, in which case after the valve 58 is closed the valves 61 and 61^a are opened, letting the surplus air from the pocket and supply pipe of the well which has been flowed escape through the 115 pipes 60 and 60^a into the supply pipe 57^a of another well, the valves 59, 58^a and 59^a being closed, after which the valve 61^a is closed and the valve 58^a opened. Therefore, it will be seen that after a well has been flowed the 120 surplus air remaining in the supply pipe and pocket of said well may be either returned to the air compressor or sent on to aid in flowing another well or wells. In some instances, however, I prefer to compound these two 125 130

methods and after the first well has been flowed and the valve 58 has been closed, I open the valves 59 and 61 and 61^a letting the surplus air escape in two directions, back 5 into the cylinder 15 and forward into the next well or wells.

I wish it to be understood that all valves or stops in connection with the turning on or off of the air supply either to or from the wells, 10 as shown in Fig. 4, are opened or closed automatically, or by hand, as conditions may warrant, which system is specifically described in my application for patent, Serial No. 121,223, filed Aug. 27th, 1902.

15 By means of the apparatus described I am enabled to utilize practically all of the air which has been compressed and use it over and over again except the small fraction which escapes with the oil into the delivery 20 tank. In cases of deep wells, this saving is of considerable commercial importance.

It will be seen at once by those familiar with the art when the fluid pressure is turned into the branch supply pipes of two or more 25 wells at once, and any one of said group of wells begins to flow, which thereby causes the pressure to lessen by reason of the oil escaping, that the fluid pressure in the supply pipes leading to the adjacent wells would at 30 once direct itself into the supply pipes of the well or wells that had been wholly or partially flowed, in other words to the point of least resistance, and to prevent this I provide each branch supply pipe with a valve mechanism 35 shown in Fig. 4 and shown in cross section on an enlarged scale in Fig. 7.

To the pipe 57 is attached the upper half 62 of a casing into which is screwed a lower half 63, provided with a rounded seat. A 40 cross piece 64 is provided with a perforated central portion 65 through which works the pin 66 of a valve 67 which is adapted to fall into its seat by its own weight. When fluid pressure is supplied through the lower part 45 of the pipe 57, it lifts said valve 67 and allows the motor fluid to pass on to the well. Any backward movement of the motor fluid, 50 however, through the pipe 57 into the main supply pipe 25 is cut off by the valve 67. Similar valves are used in connection with the pipes 57^a and 57^b.

It should be noted that the surplus air remaining in the supply pipe and pocket after a well has been flowed may be either returned to the back pressure cylinder directly, or it may be turned into one or more wells, or may be turned into one or more wells and the back pressure cylinder simultaneously, and by these means I am enabled 60 to utilize practically all of the air under pressure without waste, the very slight waste which occurs when each well is flowed being compensated for by the air drawn into the free air cylinder.

While I have thus described my invention 65 I wish it to be distinctly understood that I do not limit myself to the exact means shown and described, as it is obvious that many changes in form might be made without departing from the spirit of my invention. 70

Having thus described my invention what I claim as new and desire to secure by Letters Patent of the United States is:—

1. In an apparatus for forcing oil from wells, the combination of a single pocket arranged at or near the bottom of a well, an air supply pipe and an oil discharge pipe leading into said pocket, and an air compressing device comprising a plurality of cylinders, one of which is connected with the 80 open air and the other or back pressure cylinder is connected with the air supply pipe, whereby the air remaining in a pocket after the oil has been discharged therefrom may be utilized by being delivered into said back 85 pressure cylinder, substantially as described.

2. In an apparatus for forcing oil from wells, the combination of a single pocket arranged at or near the bottom of a well, an air supply pipe and an oil discharge pipe leading 90 into said pocket, a main air pipe connected to said air supply pipe, an air compressing device comprising two cylinders, one of which is connected with the outer air and the other of which is connected to said air supply 95 pipe, and both of said cylinders delivering their supply of compressed air into said main air supply pipe, substantially as described.

3. In an apparatus for forcing oil from 100 wells, the combination of a single pocket arranged at or near the bottom of each well, an air supply pipe and an oil discharge pipe leading into each pocket, a main air supply pipe connected to said first named air supply pipes, an air compressor composed of two cylinders, both of said cylinders being connected with the outer air, and one of said cylinders being connected with the air supply pipe that runs to each well, and a yielding 105 valve mechanism in said second named cylinder allowing atmospheric air to enter when there is no back pressure in the air supply pipe leading into each well, substantially as described.

4. In an apparatus for forcing oil from wells, the combination of a single pocket arranged at or near the bottom of each well, an air supply pipe and an oil discharge pipe leading into each pocket, a main air supply 120 pipe connected with the air supply pipes of each well, an air compressing device composed of a free air cylinder and a back pressure cylinder, connections between said air pipes that run to each well and said back 125 pressure cylinder, and means including a spring actuated piston located in said connections for causing the surplus air from

- wells that have been flowed to enter the back pressure cylinder at a uniform pressure, substantially as described.
5. In an apparatus for forcing oil from wells, the combination of a single pocket located at or near the bottom of each well, an air supply pipe and an oil discharge pipe leading into each pocket, a main air supply pipe connected with all of said individual air supply pipes, an air compressing device comprising a plurality of cylinders delivering into said main supply pipe, and connections between the individual air supply pipes for each well and half of the air compressor cylinders, whereby the surplus fluid pressure remaining after one or more wells have been flowed may be utilized, and a fluid pressure mechanism, for giving a signal when one or more wells have been discharged of fluid, substantially as described.
6. In an apparatus for forcing oil from wells, the combination of a single pocket arranged at or near the bottom of each well, an air supply pipe and an oil discharge pipe leading into each of said pockets, a main air supply pipe, connected with each of said individual air supply pipes, an air compressing device comprising two cylinders adapted to deliver compressed air into said main air supply pipe, one of said cylinders being also connected to said individual air supply pipes, and connections whereby two or more wells can be operated to flow at the same time, said connections being provided with valves which automatically prevent the motor fluid at the high pressure required to flow a well from escaping backward into the air supply pipe of a well or wells that have been flowed substantially as described.
- 40 7. In an apparatus for forcing oil from wells, the combination of an air compressor including a back pressure cylinder, and a free air or auxiliary cylinder working automatically in conjunction with each other, a pocket located at the bottom of each well, air supply pipes connected with said compressor and with said pockets respectively, a discharge pipe for each well, and means whereby said back pressure cylinder will draw in the surplus fluid pressure as well as free air when required and whereby said auxiliary cylinder will compensate for the waste of compressed air in the compounding of fluid pressure in connection with the flowing of oil wells, substantially as described.
8. In an apparatus for forcing oil from wells, the combination of an air compressor comprising a free air or auxiliary cylinder, and in conjunction with a high pressure cylinder and one or more back pressure cylinders, a main supply pipe into which all of said cylinders deliver the motor fluid, a pocket arranged at the bottom of each well, a branch supply pipe leading from said main supply pipe to the top of each pocket respectively, a delivery pipe leading from a point near the bottom of each of said pockets, and a system of piping supplied with valves whereby the surplus air pressure may be delivered to another well or wells or to said back pressure cylinder or cylinders or to both, substantially as described.
9. In an apparatus for forcing oil from wells, the combination of an air compressor comprising a free air cylinder and a back pressure cylinder, a main supply pipe into which both of said cylinders deliver compressed air, a branch supply pipe connecting said main supply pipe with each of said wells respectively, a pocket in each of said wells, with which pockets said branch supply pipes are connected respectively, a fluid pressure signal mechanism connected with each of said branch supply pipes, back pressure pipes connected to each of said branch supply pipes, a main back pressure pipe connecting all of said first named back pressure pipes with said back pressure cylinder, means for equalizing the pressure of the motor fluid delivered through said last named back pressure pipe, pipes connecting said branch supply pipes with the branch supply pipes of other wells, and suitable valves in said pipes, substantially as described.
10. In an apparatus for forcing oil from wells, the combination of an air compressor comprising two or more cylinders, a main supply pipe into which said cylinders deliver, branch supply pipes, one for each well, back pressure pipes connecting each of said branch supply pipes with one of the cylinders of said air compressor, other pipes connecting said branch pipes together, and valves in said last three named pipes whereby the surplus pressure in a well that has just been flowed may be utilized either by having the surplus air conveyed back to one of the cylinders of the air compressor, or by delivering it to one or more wells not yet flowed, or both, substantially as described.
11. In an apparatus for forcing oil from wells, the combination of an air compressor including two cylinders, a pipe for supplying air to one of said cylinders, and an equalizing device connected to said pipe, including a valve, an arm carried by said valve, a bar pivotally attached to said arm, a piston connected to said bar, connections whereby fluid pressure will operate said piston, and a spring acting against said piston to oppose said fluid pressure, substantially as described.
12. In an apparatus for forcing oil from wells, the combination of a pocket located at or near the bottom of a well, supply and discharge pipes leading into said pocket and means for equalizing the pressure of the motor fluid in the supply pipe and pocket of

- two or more wells, said means including duplex high and low back pressure and free air auxiliary cylinders working in conjunction, the first compounding the surplus fluid pressure from a well or wells that have been flowed, to flow adjacent wells, and the second to compensate for the necessary escape or waste of compressed motor fluid, substantially as described.

13. In an apparatus for forcing fluid from wells, the combination of two lifts; means arranged to carry the actuated fluid through the first of said lifts by a following action of the actuating fluid through the lift in contact with the actuated fluid; connections leading from said first lift to the source of motor fluid supply, a motor fluid connection between said lifts, means for admitting a fluid to be actuated by said lifts, and valves controlling the movement of the motor fluid and so located that a supply connection to the first of said lifts may be opened during a closure of the connection between said lifts, and whereby connection between said lifts may be opened during a closure of the connection to the source of motor fluid supply.

14. In an apparatus for forcing fluid from wells, the combination of two lifts; means arranged to carry the actuated fluid through said lifts by a following action of the actuating fluid through the lifts in contact with the actuated fluid, connections leading from one of said lifts to a source of motor fluid supply, and motor fluid connection between said lifts; means for admitting a fluid to be actuated by said lifts, and valves for controlling the movement of the motor fluid so arranged that a supply connection to one of said lifts may be opened during a closure of the connection between said lifts, and whereby a connection between said lifts may be opened during a closure of the connection to the source of motor fluid supply.

15. In an apparatus for forcing fluid from wells, the combination of two lifts; means arranged to carry the actuated fluid through said lifts by a following action of the actuating fluid through the lifts in contact with the actuated fluid; connections leading from one of said lifts to a source of motor fluid supply; a motor fluid connection between said lifts; means for admitting a fluid to be actuated by said lifts, and valves governing the movement of the motor fluid so arranged that a supply connection to one of said lifts may be opened while the connection between said lifts is closed, and whereby the connection between said lifts may be opened while the connection to the source of motor fluid supply is closed, and where the connection to the source of motor fluid supply is closed, said valves being located in a central station.

16. In an apparatus for forcing fluid from wells, the combination of two lifts; means arranged to carry the actuated fluid through the lifts by a following action of the actuating fluid through the lifts in contact with the actuated fluid; connections leading from one of said lifts to a source of motor fluid supply; a motor fluid connection between said lifts; means for admitting a fluid to be actuated by said lifts, and valves for controlling the movement of the motor fluid so arranged that a supply connection to one of said lifts may be opened while the connection between said lifts is closed, and whereby the connection to the source of motor fluid supply is closed, and where the connection to the source of motor fluid supply is closed, said valves being located in a central station.

17. In combination with two Artesian wells or the like, an apparatus comprising two lifts, one in each well; means arranged to carry an actuated fluid through said lifts by a following action of an actuating fluid through the lifts in contact with the actuated fluid; a connection with a motor fluid supply and the bottom of the lift in one of said wells, a connection between said lifts, and valves for controlling the movement of motor fluid so arranged that the connection to the motor fluid supply may be opened while the connection between the lifts is closed, and whereby the connection between the lifts may be opened while the connection to the source of motor fluid supply is closed.

18. In combination with two Artesian wells or the like, an apparatus comprising two lifts, one in each well; means arranged to carry an actuated fluid through said lifts by a following action of an actuating fluid through the lifts in contact with the actuated fluid, a connection between a motor fluid supply and the bottom of the lift in one of said wells, a connection between said lifts, and valves for controlling the movement of motor fluid so arranged that the connection to the source of motor fluid supply may be opened while the connection between said lifts is closed, and whereby the connection between said lifts may be opened while the connection to the source of motor supply fluid is closed, said valves being located in a central station.

19. In combination with two Artesian wells or the like, an apparatus comprising two lifts, one in each well; means arranged to carry liquids through said lifts by a following action of an actuating fluid through the lifts in contact with said liquids; connections leading from the bottoms of said lifts to a source of motor fluid supply; motor fluid connections between said lifts, and valves for controlling the movement of motor fluid so arranged that a connection with the source of motor fluid supply may be opened while the connection between said lifts is closed, and whereby the connection between said lifts may be opened while the connection to the source of motor fluid supply is closed, while the connection to the source of motor fluid supply is closed, and whereby the connection from the first lift to an exhaust may be opened, while the connection of the second lift and the source of supply is opened.

the movement of the motor fluid so arranged that the connection between the motor fluid supply and the first of said lifts may be opened while the connection between said lifts is closed, whereby the connection between said lifts may be opened while the connection between the first of said lifts and the motor fluid supply is closed, and whereby a connection between said second lift and the 10 motor fluid supply may be opened while the connection between said lifts is closed.

20. The combination with a plurality of Artesian wells, of lifts, one located in each of said wells and comprising a pocket, a supply 15 and a delivery pipe leading into said pocket, means for furnishing a supply of compressed air for actuating the liquid collecting in said pockets by a following action of the actuating fluid through said lifts in contact with 20 the actuated liquid, a pipe connecting the air pipes running to the bottom of each well with the source of compressed air, branch pipes connecting said air supply pipe with the pipes leading into each well successively, re- 25 turn pipes leading back from each well back to the air compressor, and a valve located in each of said pipes, whereby the entire air supply may be turned into one pocket, a portion of said air supply may be turned from 30 said pocket into a succeeding pocket to assist in flowing a second well, and whereby the

surplus air still under pressure may be returned to the air compressing means.

21. The combination with a plurality of Artesian wells, of lifts, one located in each of 35 said wells and comprising a pocket, a supply and a delivery pipe leading into said pocket, means for furnishing a supply of compressed air for actuating the liquid collecting in said pockets by a following action of the actuating 40 fluid through said lifts in contact with the actuated liquid, a pipe connecting the air pipes running to the bottom of each well with the source of compressed air, branch pipes connecting the air supply pipes leading into 45 each well successively, return pipes leading from each well back to the air compressor, a valve located in each of said pipes, whereby the entire air supply may be turned into one pocket, a portion of said air supply may be 50 turned from said pocket into a succeeding pocket to assist in flowing a second well, and whereby the surplus air still under pressure may be returned to the air compressing means, and devices for showing the pressure 55 in each of said wells.

In testimony whereof, I affix my signature, in presence of two witnesses.

JOHN W. WAITZ.
